UNITED STATES PATENT OFFICE

WILLIAM DALE, OF WASHINGTON, DISTRICT OF COLUMBIA.

IMPROVEMENT IN VAULT-COVERS.

Specification forming part of Letters Patent No. 156,411, dated November 3, 1874; application filed December 30, 1873.

To all whom it may concern:

Be it known that I, WILLIAM DALE, of the city of Washington, in the District of Columbia, have invented an Improvement in Vault-Covers, of which the following is a specification:

Figure 1 is a perspective view of my improved cover, showing a dish, having across the inner surface of its bottom plate ribs, to act in retaining the material with which it is filled, and an inwardly-projecting ledge or pins upon the inner surface of its vertical portion for the same purpose, while the bottom plate is perforated for the purpose of allowing water to escape, and air to enter to facilitate the hardening of the cement. Fig. 2 is a transverse section, showing the position of the parts above alluded to.

Corresponding letters denote corresponding parts in both figures.

This invention relates to that class of vault-covers which consist of a dish or case of metal filled with concrete, cement, bricks, or other kind of material, it being designed as an improvement upon the one patented to me, on the 30th day of March, 1869, as the assignee of George H. Palmer.

My present improvement consists in perforating the bottom of the dish, for a purpose presently to be explained.

I now use in most instances cement to fill the cavity of the dish, and up to the date of my invention no means had been provided for the escape of the moisture from that portion thereof which is in the lower portion of said dish; and, as the upper portion of the filling soon becomes hardened, the moisture remains in the great body of the same, and

prevents it from hardening, and, finally, deteriorates the same to such an extent that it does not become as hard as that upon the surface.

In order that a remedy may be provided for the escape of such moisture, and thus this difficulty remedied, holes D D are provided in the bottom plate of the dish, sufficient in number to allow any water which may be in the filling at the time of placing it in said dish, to pass off either by being drained through them or by evaporation, while they at the same time permit the air to come in contact with a considerable portion of the under surface of the filling, and thus aid in hardening the same.

I have described my invention as applicable to vault-covers only; but it is apparent that it is equally applicable to man-traps or any other form of opening in streets or sidewalks.

I do not in this case lay any claim to the dovetailed ribs B, or inwardly-projecting ledge or pins C or C', as they are covered by a claim in another case previously presented by me.

I claim—

A dish, for the reception of cement or other material, for forming a vault-cover, having in its lower surface a series of openings for the escape of moisture and the admission of air, substantially as and for the purpose set forth.

In testimony whereof I have signed my name to this specification in the presence of two subscribing witnesses.

WILLIAM DALE.
